his Attorney

UNITED STATES PATENT OFFICE.

GRAIG WAYNE ANDERSON, OF COLUMBUS, OHIO.

HAIR CURLER AND WAYER.

Application filed November 26, 1926. Serial No. 150,779.

The invention relates to hair curling and waving devices. It is frequently desirable to have a portion of the lock or tress curled with the remainder waved, and the chief object of the invention is to provide means whereby this can be accomplished neatly, effectively and with facility. Another object of the invention is an improved means for use in connection with the curling and waving device to treat the curled and waved tress so that the curled and waved effect produced by the instrument will become fixed or "permanent" so called. Other objects will appear from the following disclosure.

The invention is embodied in the example herein shown and described, the features of novelty being finally claimed.

In the accompanying drawing—

Figure 1 is a side view of the curling and waving instrument.

Fig. 2 is an elevation looking at the left hand side of Fig. 1.

Fig. 3 is a detail in partial section illustrating features of the curling elements.

Fig. 4 is a side view of the heating device.

Fig. 5 is an end view of the same.

In the views 10 designates the curling rod and 11 the concave clamping blade cooperating by longitudinal association with the 30 curling rod. The said curling rod and concave blade are each provided with a finger piece and are hinged together, as shown, in spreading relation upon a pin 12 around which is a coil spring having extended ends 35 engaging the finger pieces to clamp the two members together after a tress has been curled in spiral fashion about the curling rod.

Hinged to the outer opposite ends of the 40 pin 12 in nesting fashion is a plurality of longitudinally concaved blades 13 adapted to be opened and closed on said pin 12 somewhat like the ribs of a collapsible fan, said rods 13 being shown in Figs. 1 and 2 as being in a partially opened or separated state.

When a tress of hair, near the scalp, has 50 been wound around the curling rod from the hinged end outward and clamped thereto the remainder of the tress can be woven back and forth between the successive concave blades; or it can be woven around one or more of the blades after the latter has been closed down on the curling elements. The

device is capable of varied use according to the length of the hair and the effect to be 55 produced.

After the tress has been applied to the curling and waving elements or either of them it can be given a treatment of moisture and heat, an appropriate solution of ammonia together with borax being employed to impart permanence or stability to the curled or waved hair. The heating device for doing this consists of two metallic covers or containers 14 hinged together upon a pin 15 so as to fold together like the halves of a book. Springs 16 are provided tending to hold these containers yieldingly together. The container members of the heater are provided with projecting finger pieces 17 70 riveted thereto near the middles of the outer sides of the container members at their hinged portions so that said container portions can be conveniently separated by suitable pressure of the thumb and finger of the 75 hand.

The inner sides of the container members are equipped with electrical heating elements 18 fixed therein, they being suitably insulated and each having electrical conductors 80 leading thereto so that they can be energized through an ordinary attachment to an ordinary lamp socket (not shown).

In practice when the tress has been taken up in the curling and waving instrument there is wrapped about it one or more pads of cotton or other suitable fibrous material 20 moistened with a solution of ammonia and sprinkled with borax, the pad thus treated being wrapped in a suitable paper (not shown). The instrument thus prepared is inserted between the opened leaves or sides of the heater so that when said sides are released the pad and the contained instrument and tress are held while another tress is being prepared in the same way. After all the tresses to be treated are gathered up in the necessary number of instruments and heaters the current is turned on and the heat applied for from, say six to fourteen minutes according as may be necessary by reason of the susceptibility of the hair to fixation by the treatment. The release of the tresses after this treatment is quite simple because after the curling and waving instrument is removed from the heater and the pad removed

the instrument can be withdrawn from the tress upon slightly separating the blades, the hair being then adjusted by appropriate or usual manipulation.

5 The forms of the parts can be changed without departing from the gist of the invention as claimed.

What I claim is:

1. Means for curling and waving hair comprising a curling rod, a longitudinally concaved blade cooperating therewith and a plurality of longitudinally concaved blades in hinged relation to said curling rod and in superposed nesting relation to one another 15 whereby a tress curled on the rod can be waved by the plurality of blades.

2. Means for curling and waving hair comprising a curling instrument and a plurality of longitudinally concaved blades in 20 hinged relation to said curling instrument

whereby a tress curled on the instrument can be waved by the plurality of blades.

3. Means for curling and waving hair comprising a curling instrument, a plurality of longitudinally concaved blades in hinged 25 relation to the curling instrument whereby a tress curled on the instrument can be waved by the plurality of blades and a heater for the tress and instrument consisting of a pair of clamping covers having electric heating 30 elements therein.

4. In means for curling and waving hair, a heating device therefor consisting of a pair of hinged containers, each container having an electric heating element secured therein, 35 and yielding means tending to hold said containers in closed relation respecting each other on the curling and waving means.

Graig Wayne Anderson.
